HANDLE FOR PORTABLE PICTURE SCREENS

Laurel E. Cooley, Sr., and Laurel E. Cooley, Jr., La
Grange, and Carl O. Plaul, Chicago, Ill.

Application May 25, 1956, Serial No. 41,660

Term of patent 3½ years

(Cl. D61—1)

Fig. 1 is a side view of a handle for portable picture screens showing our new design.

Fig. 2 is an end view taken from the left of Fig. 1.

Fig. 3 is a top plan view.

Fig. 4 is a bottom plan view.

Fig. 5 is a sectional view taken on the line 5—5 of Fig. 1.

We claim:

The ornamental design for a handle for portable picture screens, as shown.
